(57) **CLAIM**

We claim the ornamental design for a utility vehicle, as shown and described.

DESCRIPTION

FIG. 1 is a left front perspective view of a utility vehicle with cab doors and a roof;

FIG. 2 is a front view of the utility vehicle of FIG. 1;

FIG. 3 is a rear view of the utility vehicle of FIG. 1;

FIG. 4 is a left side view of the utility vehicle of FIG. 1;

FIG. 5 is a right side view of the utility vehicle of FIG. 1;

FIG. 6 is a top view of the utility vehicle of FIG. 1;

FIG. 7 is a left front perspective view of the utility vehicle of FIGS. 1-6 shown in an alternate configuration without cab doors and a roof;

FIG. 8 is a front view of the utility vehicle of FIG. 7;

FIG. 9 is a rear view of the utility vehicle of FIG. 7;

FIG. 10 is a left side view of the utility vehicle of FIG. 7;

FIG. 11 is a right side view of the utility vehicle of FIG. 7; and, FIG. 12 is a top view of the utility vehicle of FIG. 7.

The broken line shown in the drawings are for the purpose of illustrating portions of the article that form no part of the claimed design.
